UNITED STATES PATENT OFFICE.

WARREN M. OSBORN, OF CHICAGO, ILLINOIS, ASSIGNOR TO CHICAGO MALLEABLE CASTINGS COMPANY, OF CHICAGO, ILLINOIS, A CORPORATION OF ILLINOIS.

TIE-PLATE FOR RAILS.

1,334,673.

Specification of Letters Patent. Patented Mar. 23, 1920.

Application filed July 16, 1919. Serial No. 311,303.

To all whom it may concern:

Be it known that I, WARREN M. OSBORN, a citizen of the United States, residing at Chicago, in the county of Cook and State of Illinois, have invented certain new and useful Improvements in Tie-Plates for Rails, of which the following is a specification, reference being had therein to the accompanying drawing.

10 My invention relates to tie plates for railroad rails, its object being to provide new and improved means for utilizing the same plates for rails having bases of different or varying cross-sections or sizes.

15 The invention consists of the matters hereinafter described and then pointed out in the claims.

In the drawings Figure 1 is a cross-sectional view of the plate and an associated rail of relatively small size with the spikes that engage the rail base and their heeling pieces in position, parts being in perspective and broken away for convenience of illustration;

25 Fig. 2 is a detail sectional view on the line 2—2 of Fig. 1;

Fig. 3 is a detail perspective view of one of the spike-heelers shown in Fig. 2;

30 Fig. 4 is a detail perspective view of a modified form of spike-heeler, and

Fig. 5 is a detail sectional view showing certain parts with the modified heeler piece in position.

35 In the drawing the reference letter A represents the head of a rail, B its base, and C the web uniting the head and base.

The plate consists of the usual body 5 provided near one side with an overhanging flange 6 which extends the full length of the 40 plate to engage the corresponding side of the rail base, and with spike holes 7 outside the base of the flange to receive the spikes for that side of the plate, the flange preferably making a drive-fit with the rail base. The 45 plate also is provided near its opposite side with an abutment 8 which is interrupted by the spike holes 9 to receive the usual spikes 10 which are driven into the underlying tie to assist in holding the rail on the plate. The 50 Each spike hole 9 is provided at its outer margin with a spike-heeling lug 11 against which the heel or back portion of the spike abuts when the spike is driven to place, so that the spike is buttressed against the 55 strains arising from the tendency of the rails

to spread or tip sidewise. The inner faces of the lugs 11 are inclined inwardly and downwardly so that as the spike is driven to place it wedges against the rail base.

The spike holes 9 are elongated in the 60 cross-sectional line or width of the plate so that spikes may be driven through them into the underlying tie at different points or locations according to differences in the size or cross-section of the rail base to hold it in position on the plate. The distance between the abutment 8 and the vertical wall of the flange 6 is sufficient to accommodate the base of a large or heavy rail of any standard size or cross-section, say of a 90 pound rail, and when such rail is in position its base fills the space between these opposite parts and the spikes for the holes 9 will pass through the outer portions of these holes and abut against the heeling-lugs 11 with their heads 65 overlying the rail base. When a rail is used having a smaller base, say a 65 pound rail, its base being narrower than that of the heavier rail permits the spikes for the holes 70 9 to pass through the intermediate or inner portions of these holes, according to the width of the rail base, and the spikes then 75 will not abut against the heeling-lugs 11, and in order to heel them up I provide spike-heelers which may be interposed between the 80 spikes and the heeling-lugs 11 and which when in position will act upon the spikes in 85 the same manner and with the same effect as the lugs themselves.

The spike-heelers 12 are individual pieces 90 of metal adapted to be inserted in the outer portions of the elongated spike holes 9 and are of sufficient cross-sectional area to fill 95 up the gap that otherwise would exist between a spike 10 and the lug 11, it being obvious that they may be made of different sizes in this respect so that such gaps of varying widths may be filled according 100 as the size of the rail base may vary. In Fig. 1, for illustration, I show a spike-heeler 12 adapted to fill the gap caused by the decrease in width of the base of a 65 pound rail in comparison with the width 105 of a rail base that itself would cause the spike 10 to be heeled by the lug 11. Preferably the spike heelers interlock with the plate 5. In the form shown in Figs. 1, 2 and 3 the heeler is provided along the outer and lateral edges of its lower end with suitable flanges 13 and 14, respectively, which 110

- rest in correspondingly countersunk portions of the outer and lateral walls of the lower ends of the spike holes. In this form the heelers are inserted into the spike holes from 5 below, and their flanges prevent them from being dislodged upwardly, while their lower ends are flush with the bottom of the plate and rest on the underlying tie, so that they are held against accidental displacement.
- 10 In the form shown in Figs. 4 and 5 the heeler is plain at its lower end and is dropped into the spike hole from above, and it is provided with intermediate lateral flanges 15 which rest upon the upper ends 15 of the walls of the spike holes, and also with an inner shoulder 16 upon which the spike-head bears, the heeler thus being held against accidental displacement.
- The heelers 12 are correspondingly shaped 20 upon their outer faces to conform to and fit against the lugs 11, and their inner faces 17 are preferably inclined inwardly and downwardly so that they exert an inwardly wedging action against the spikes when the 25 latter are driven to place. When the plate is not provided with lugs 11 the heelers 12 bear against the outer ends or walls of the spike holes 9.

In using the heelers they are placed in 30 position in the outer ends of the spike holes, after the rail base is positioned under the flange 6, and the spikes 10 are then driven to place; the heelers wedge the opposite side of the rail base in position beneath the 35 flange and abut against the spikes and heel them up in the same way as the lugs 11.

I claim:

1. A tie plate for rails comprising a body 40 having elongated spike holes extending transversely thereof, and spike-heeling pieces fitting in the outer portions of the spike holes between the spikes and the outer walls of the holes.

2. A tie plate for rails comprising a body having elongated spike holes extending 45 transversely thereof, spike-heeling lugs at the outer margins of said holes, and spike-heeling pieces fitting in the outer portions of the spike holes between the spikes and the lugs.

3. A tie plate for rails comprising a body having elongated spike holes extending transversely thereof, and spike-heeling pieces fitting in the outer portions of the holes and having flanges coöperating with 50 the walls of the spike holes.

4. A tie plate for rails comprising a body having elongated spike holes extending transversely thereof, and spike-heeling pieces fitting in the outer portions of the 60 holes and having flanges at their lower ends countersunk in the walls of the spike holes.

5. A tie plate for rails comprising a body having elongated spike holes extending transversely thereof, a lug extending above 65 the outer end of each hole, and spike-heeling pieces fitting between the spikes and lugs, and interlocking with the plates.

6. A tie plate for rails comprising a body, an overhanging flange to engage one side 70 of the rail base, the body having elongated spike holes extending transversely thereof, a lug extending above the outer end of each hole, and a spike-heeling piece fitting between the lug and the spike in its corresponding hole, the lower end of the heel- 75 ing piece having outer and lateral flanges, and the lower end of the spike-hole being countersunk to receive the flanges.

In testimony whereof I affix my signature 80 in presence of two witnesses.

WARREN M. OSBORN.
